(57) **CLAIM**

The ornamental design for an apparatus for measuring body fat, as shown and described.

DESCRIPTION

FIG. 1 is a top plane view of the apparatus for measuring body fat according to the present invention;

FIG. 2 is a bottom view of the apparatus of FIG. 1;

FIG. 3 is a right side perspective view of the apparatus of FIGS. 1 and 2;

FIG. 4 is a left side perspective view of the apparatus of FIGS. 1-3;

FIG. 5 is a front elevation view of the apparatus of FIGS. 1-4;

FIG. 6 is a side elevation view of the apparatus of FIGS. 4 and 5; and,

FIG. 7 is a rear elevation view of the apparatus of FIGS. 1-6.
